W. C. CUTLER

AUTOMATIC DISPLAY DEVICE

Filed August 8, 1923

INVENTOR.

William C. Butler

BY

ATTORNEY.

UNITED STATES PATENT OFFICE.

WILLIAM C. CUTLER, OF GLENDALE, CALIFORNIA, ASSIGNOR TO ISABELLA M. CUTLER, OF GLENDALE, CALIFORNIA.

AUTOMATIC DISPLAY DEVICE.

Application filed August 8, 1923. Serial No. 656,379.

My invention relates to improvements in exhibiting mechanisms, the object of the invention being the provision of a mechanism for automatically exhibiting one card or sign at a time, allowing the same to remain in view position a predetermined time until all cards or signs are displayed, one at a time, then returning the full pack of cards or signs to a starting position; this machine being constantly operated from and by a suitable motor;

Another object of this invention is to provide a simple and attractive displaying machine of this character which can use a large number of carriers whereby a great variety of subjects may be displayed;

Another object is to secure the necessary card shifting movement and not disturb the card displaying action;

Another object is to provide a novel card elevating or displaying means, and operatively associated therewith a novel means for restoring the displaying means to normal position;

Another object is to produce a device of this character which will be reliable in operation and have a minimum liability of getting out of working order;

Another object is to insure the locking of some of the parts while other parts are operating, and to equalize the power and eliminate noise;

With these and other objects in view, the invention consists in certain novel features of construction and combinations and arrangements of parts, as will be more fully hereinafter described and pointed out in the claims.

In referring to the accompanying drawings,

Fig. 1 is a cross-sectional view of my device with parts broken out for clearness. Fig. 2 is a rear elevation of the mechanism and cabinet with the door removed. Fig.

3 is a detail view of the card carrying belt.

1 is the case for housing the working parts of my device which is driven by the electric motor 70 receiving power through the wires 8 and 11, with a controlling cut out switch 9. The driving pulley 71 is attached to the grooved pulley 47 through the

belt 72. The grooved pulley 47, to which is attached the pinion 49, both rotate on the shaft 48, which is rotatively attached to the case 1, at 78. The pinion 49 meshes with the gear wheel 38, which is tied to the case 1 through the bearing 40. The lower end of the connecting rod 34 is pivoted to the gear wheel 38, by the pin 37; the upper end at 33 is pivoted to the lower end of the rack 10, rack 10 being guided on one side by the flanged roller bearings 12, which are rotatively attached to the side of the case 1. The other side of the rack 10 having teeth 13 part way up its length, meshes with the pinion 25, which is attached to the gear wheel 22, both rotating on the stub-shaft 81 which is attached to the case 1; the gear wheel 22 meshing with the rack 35, the upper end of which is bent L-shaped at 14, extending across the case 1, and carrying the U-shaped lugs 21, for holding the card wires 15, which are attached to the cards 19; the rack 35 running in the groove 7, both sides being guided in their up and down movement by the guides 3 and 20. The belts 51, made of metal or other suitable material, having lugs 16 pressed out of the same leaving the holes 76, run over the pulleys 18, which run on the stub-shaft 79, and over the flanged belt wheels or pulleys 50, both of which are secured to the shaft 48, which in turn is pivoted to the sides of the case 1 at 78. Thus starting the motor 70, rotates the grooved pulley 47, carrying with it the pinion 49, which in turn rotates the gear wheel 38, causing an up and down motion of the rack 10, with the teeth 13, which are omitted from 82 to the upper end; and is so timed that the rack 35 has carried the card 19 to a display position through the opening 2.

When the pinion 25 gets to the end of the teeth 13 at 82, the pinion 25 is held in this position by the friction clutch 23 until the rack is carried down and up again through that part of the same having no teeth, thus leaving the card 19 on display during this period; and when the teeth in pinion 25 again mesh with the rack 10 in its upward movement it carries the card 19 back to storing position, leaving the ends of the wires

15, which are attached to the upper ends of the cards 19 and extend over far enough to lie between the lugs 16, on the belts 51, permitting the cards 19 to hang straight down 5 parallel with each other without interference; so that a large number of cards may be kept in compact arrangement in this space, always having sufficient space for properly raising and lowering a card 19, to 10 and from the belts 51 which are tied to the flanged belt wheel 50 so they will not slip when power is applied. The slotted lugs 36 are attached to the flanged belt wheel 50 at 15 80, and are so constructed that when the gear wheel 38, carrying the pin 37, rotates, this pin 37 will enter a slot at an angle to shift the grooved pulleys 50, just far enough to put the succeeding card in position to be carried by the U-shaped lug 21 to displaying 20 position. After all cards have been displayed, one at a time in this manner, and at the last movement of the pin 37, entering the slot in lug 36, the pin 62 connects with the lever 60 at 61, forcing the lever 60, guided 25 by the roller bearing 63, up, causing the levers 66 and 68, which are pivoted at 69 and 67 and run in a slot 65 over the pin 64, to straighten up, forcing the rack 56, to mesh with the gear wheel 38, thus throwing 30 all cards 19 back to starting position, and causing the pin 57 to connect with the lever 60 at 59, thus releasing the rack 56, which is attached to the flanged belt wheel 50 at 58, from the gear wheel 38, again allowing the 35 cards 19 to be displayed one at a time. It can be understood that when the weight of the card 19 is carried up by the motor 71, the motor having more weight exerted against it, would run at less speed than when the 40 card is going down; to equalize this weight I have employed a friction clutch 43, tied to the case 1 at 42, made of metal hollowed out in the center, into which is placed a spring 45, and a piece of fiber 41 shouldered at 46, to hold the tension of the spring 45, and allowed to protrude far enough to drag 45 on the cam 39, which is attached to and runs with the gear wheel 38, and so adjusted on the same as to cause a braking action when 50 the card 19 is coming down. The end of the set screw 44 connects with the spring 45, allowing adjustment on the clutch 43. To insure the card carrying belts 51 remaining in the position from which the card 19 is raised 55 until it is again returned, I employ a braking action on the sides of the belt wheel 50 on the bearing 73 which is attached to the case 1, to which is tied at 55, a T-shaped bar 58, having adjustable means for dragging 77 60 on the sides of the belt wheel 50, held by the screws 52 and 54. The motor 70 is held in place by a block 75, attached to the case 1, to which the motor bracket 74 is attached. 65 The bracket 26 is tied to the case 1 at 27 and supports the screw 28 over which is a

spring 29, the tension of which is adjusted by turning the screw 28, thus causing flat spring 31, which is tied to the case 1 at 32, to exert pressure against the fiber ring 23, on the hub 24, at the proper time to hold the 70 load to be carried by it.

Having described my invention, what I claim is,—

1. In an automatic display device belts, cards spaced along and suspended from said belts; each card adapted to be individually raised from, and returned to, said belts, pulleys over which said belts run, a card elevator reciprocal thru a path intersecting the path of travel of said belt, a revolute member, connections between said revolute member and said elevator for imparting, with each revolution, a reciprocal movement to said elevator with an interval of rest for said elevator after each ascension, one of said pulleys being provided with a given number of tangential grooves, and a pin protruding from said revolute member disposed to pass thru a tangential groove, with each revolution of said member. 75 80 85 90
2. In an automatic display device belts, cards spaced along and suspended from said belts; each card adapted to be individually raised from, and returned to, said belts, pulleys over which said belts run, a card elevator reciprocal thru a path intersecting the path of travel of said belt, a revolute member, connections between said revolute member and said elevator for imparting, with each revolution, a reciprocal movement to said elevator with an interval of rest for said elevator after each ascension, one of said pulleys being provided with a given number of tangential grooves, and a pin protruding from said revolute member disposed to pass thru a tangential groove, with each revolution of said member. 95 100 105 110 115
3. In an automatic display device a reciprocal card elevator, power driven means for causing the elevator to ascend and descend with an interval of rest after each ascension, cards, a card carrier adapted to be advanced intermittently in a fixed path intersecting the path of travel of the elevator, and power driven means synchronized with the elevator and operating just prior to each ascension to advance the card carrier, and means whereby the power driven means is temporarily disconnected from the elevator to provide for the period of rest, and a brake acting on said card elevator to hold same in elevated position during said period. 120 125 130
4. In an automatic display device a reciprocal card elevator, power driven means

- for causing the elevator to ascend and descend with an interval of rest after each ascension, cards, a card carrier adapted to be advanced intermittently in a fixed path 5 intersecting the path of travel of the elevator, and power driven means synchronized with the elevator and operating just prior to each ascension to advance the card carrier, and means whereby the power driven 10 means is temporarily disconnected from the elevator to provide for the period of rest, and a brake constantly acting on the elevator to provide for minimizing the load changes of the elevator and for holding the 15 elevator frictionally in elevated position.
5. In an automatic display device, a movable card carrier, cards spaced along same in direction of movement, a card elevator reciprocal in a path which intersects the path 20 of travel of the card carrier, and power means connected to the card elevator and card carrier so that the elevator reciprocates while the card carrier is shifted step by step to bring successive cards into the 25 path of movement of the elevator while same is below the card carrier, means whereby the card elevator is temporarily disconnected from the power means while the elevator is in display position, and friction means acting 30 constantly on the elevator.
6. In an automatic display device, a pair of spaced belts, pulleys positively driving said belts, cards, a wire to each card passing thru the respective card and protruding 35 from each end; said cards suspended on said belts with the wires transversely disposed and with the ends of the wires protruding over respective belts, a card elevator reciprocal thru a path intersecting the path of 40 travel of said belts, said elevator adapted on each reciprocation to raise a card within its path to display position and return same to original position and to move below the original position of the returned card before 45 beginning a subsequent ascension; said elevator when below said original position of the returned card, permitting of advance movement of said belts to bring a succeeding card into the path of travel of said elevator. 50
7. In an automatic display device, a pair of spaced belts, pulleys positively driving said belts, cards, a wire to each card passing thru the respective card and protruding 55 from each end; said cards suspended on said belts with the wires transversely disposed and with the ends of the wires protruding over respective belts, a card elevator reciprocal thru a path intersecting the path of 60 travel of said belts, said elevator adapted on each reciprocation to raise a card within its path to display position and return same to original position and to move below the original position of the returned card before 65 beginning a subsequent ascension; said elevator when below said original position of the returned card, permitting of advance movement of said belts to bring a succeeding card into the path of travel of said elevator. 70
8. In an automatic display device, a pair of spaced belts, pulleys positively driving said belts, cards, a wire to each card passing thru the respective card and protruding from each end; said cards suspended on said belts with the wires transversely disposed and with the ends of the wires protruding over respective belts, a card elevator reciprocal thru a path intersecting the path of travel of said belts, said elevator adapted on each reciprocation to raise a card within its path to display position and return same to original position and to move below the original position of the returned card before 75 beginning a subsequent ascension; said elevator when below said original position of the returned card, permitting of advance movement of said belts to bring a succeeding card into the path of travel of said elevator, and means for imparting such advance movement to said belts and pulleys while the elevator is below the normal position of the returned card. 80
9. In an automatic display device, a pair of spaced belts, driving means and guiding means for said belts to drive and guide same simultaneously; means arranged to cause a portion of the length of said belts to pass thru a horizontal path, cards spaced along, and suspended freely by, said belts, a reciprocal card elevator reciprocal thru a vertical path which intersects the said horizontal path, whereby intermittent advance of 85 said belts with synchronized reciprocation of said elevator will cause each successive card to be raised, displayed and returned to the belts, a constantly revolute pinion, connections between said pinion and elevator whereby a card is raised, displayed and returned during each revolution of the pinion, means on said pinion to connect with one of said driving means at each revolution to advance the belts one card at a time, 90 a rack movable in a given direction to reverse the driving means and belts, said rack movable into and out of mesh respectively with said pinion, means for moving said rack into mesh with said pinion after the 95 belts have been intermittently moved a given distance forwardly, and other means to move said rack out of mesh with said pinion after the belts have been returned a given distance. 100
10. In an automatic display device, a pair of spaced belts, pulleys positively driving said belts, cards, a wire to each card passing thru the respective card and protruding from each end; said cards suspended on said belts with the wires transversely disposed and with the ends of the wires protruding over respective belts, a card elevator reciprocal thru a path intersecting the path of travel of said belts, said elevator adapted on each reciprocation to raise a card within its path to display position and return same to original position and to move below the original position of the returned card before beginning a subsequent ascension; said elevator when below said original position of the returned card, permitting of advance movement of said belts to bring a succeeding card into the path of travel of said elevator. 115
11. In an automatic display device, a pair of spaced belts, pulleys positively driving said belts, cards, a wire to each card passing thru the respective card and protruding from each end; said cards suspended on said belts with the wires transversely disposed and with the ends of the wires protruding over respective belts, a card elevator reciprocal thru a path intersecting the path of travel of said belts, said elevator adapted on each reciprocation to raise a card within its path to display position and return same to original position and to move below the original position of the returned card before beginning a subsequent ascension; said elevator when below said original position of the returned card, permitting of advance movement of said belts to bring a succeeding card into the path of travel of said elevator. 120
12. In an automatic display device, a pair of spaced belts, pulleys positively driving said belts, cards, a wire to each card passing thru the respective card and protruding from each end; said cards suspended on said belts with the wires transversely disposed and with the ends of the wires protruding over respective belts, a card elevator reciprocal thru a path intersecting the path of travel of said belts, said elevator adapted on each reciprocation to raise a card within its path to display position and return same to original position and to move below the original position of the returned card before beginning a subsequent ascension; said elevator when below said original position of the returned card, permitting of advance movement of said belts to bring a succeeding card into the path of travel of said elevator. 125
13. In an automatic display device, a pair of spaced belts, pulleys positively driving said belts, cards, a wire to each card passing thru the respective card and protruding from each end; said cards suspended on said belts with the wires transversely disposed and with the ends of the wires protruding over respective belts, a card elevator reciprocal thru a path intersecting the path of travel of said belts, said elevator adapted on each reciprocation to raise a card within its path to display position and return same to original position and to move below the original position of the returned card before beginning a subsequent ascension; said elevator when below said original position of the returned card, permitting of advance movement of said belts to bring a succeeding card into the path of travel of said elevator. 130

10. In an automatic display device, a pair of spaced belts, driving means and guiding means for said belts to drive and guide same simultaneously; means arranged to cause a 5 portion of the length of said belts to pass thru a horizontal path, cards spaced along, and suspended freely by, said belts, a reciprocal card elevator reciprocal thru a vertical path which intersects the said horizontal 10 path, whereby intermittent advance of said belts with synchronized reciprocation of said elevator will cause each successive card to be raised, displayed and returned to the belts, a constantly revolute pinion, connections 15 between said pinion and elevator whereby a card is raised, displayed and returned during each revolution of the pinion, means on said pinion to connect with one of said driving means at each revolution 20 to advance the belts one card at a time, a rack movable in a given direction to reverse the driving means and belts, said rack movable into and out of mesh respectively with said pinion, means for moving said rack in- 25 to mesh with said pinion after the belts have been intermittently moved a given distance forwardly, and other means to move said rack out of mesh with said pinion after the belts have been returned a given distance, 30 said elevator being reciprocal in its path to a point well below the belts to provide for moving the belts while the elevator is still below said belts; said last named three means all being timed to accomplish their 35 respective movements of said belts at times during which the card elevator is below said belts.
11. In an automatic display device, a pair of spaced belts each having lugs spaced 40 along a part of their length with the lugs of one belt registering with the lugs of the other belt, wires removably suspended transversely of the spaced belts; said wires being held spaced from each other in parallel re- 45 lation by said lugs, cards, one for each wire, each suspended from the corresponding wire between said belts, means for inter- 50 mittently moving said belts forwardly one card at a time, and a card elevator recipro- 55 cal in a path intersecting the path of travel of the card carrying portion of said belts, said elevator reciprocal from a point below said belts to a point above said belts and arranged to lift a wire and a card which is in its path.
12. In an automatic display device, a constantly reciprocating member, a reciprocal card elevator intermittently driven by the reciprocating member so that a card after 60 being raised will remain in display position for an interval during which the elevator is out of engagement with the reciprocating member, a card carrier adapted to be advanced across the path of movement 65 of said elevator whereby cards may be suc- cessively raised, displayed and returned to the carrier, and braking means acting on said elevator while same is out of driven engagement with the reciprocating member. 70
13. In an automatic display device, a constantly reciprocating rack, a card elevator, a card carrier movable across the path of movement of the rack, another rack driving said card elevator, a gear so associated with the racks that the first named rack will be intermittently out of mesh with the gear so that the card elevator will have an interval of rest after each ascension, and friction means acting on said gear to hold the elevator frictionally during the intermission. 80
14. In an automatic display device, a movable card carrier, a reciprocal elevator moving in a path crossing that of the card carrier, means for advancing the card carrier intermittently so that a card is lifted from the card carrier and returned after being displayed while the carrier is temporarily motionless, a pinion, a reciprocal rack connected to said elevator and constantly in mesh with said pinion, a constantly reciprocating rack meshing intermittently with said pinion, and a brake arranged to hold the elevator and pinion motionless while the last named rack is out of mesh with said pinion. 85
15. In an automatic display device, a movable card carrier, a reciprocal elevator moving in a path crossing that of the card carrier, means for advancing the card carrier intermittently so that a card is lifted from the card carrier and returned after being displayed while the carrier is temporarily motionless, a pinion, a reciprocal rack connected to said elevator and constantly in mesh with said pinion, a constantly reciprocating rack meshing intermittently with said pinion, and power means for constantly reciprocating said last named rack, a braking member for said gear, and friction means in contact with said braking member. 90
16. In an automatic display device, a card elevator, cards, a card carrier for same movable to feed cards successively to the elevator, constantly moving power means adapted to intermittently engage the elevator to create successive advance and retractile movements thereof with accompanying intermission for display, and braking means associated with said elevator to hold same when not engaged by said constantly moving means. 100
17. In an automatic display device, a card elevator, a rack moving therewith, a pinion meshing constantly with said rack, another rack, power means for constantly reciprocating said last named rack, the latter rack arranged to mesh with the pinion throughout a part only of each advance and retrograde stroke, and a brake for said pinion. 110
18. In an automatic display device, a card elevator, a rack moving therewith, a pinion meshing constantly with said rack, another rack, power means for constantly reciprocating said last named rack, the latter rack arranged to mesh with the pinion throughout a part only of each advance and retrograde stroke, and a brake for said pinion. 120
19. In an automatic display device, a card elevator, a rack moving therewith, a pinion meshing constantly with said rack, another rack, power means for constantly reciprocating said last named rack, the latter rack arranged to mesh with the pinion throughout a part only of each advance and retrograde stroke, and a brake for said pinion. 130

18. In an automatic display device having a card elevator, means for causing the elevator to ascend and remain motionless for an interval in display position, and subsequently descend, said means comprising a rack operating the elevator directly, a pinion meshing constantly therewith, another rack constantly reciprocating and arranged to engage the pinion for a part only of each of its strokes, and a brake to hold the pinion motionless while the last named rack is out of engagement with the pinion. 20
19. In an automatic display device having a card elevator, means for causing the elevator to ascend and remain motionless for an interval in a display position, and subsequently descend, said means comprising a rack operating the elevator directly, a pinion meshing constantly therewith, another 25
